UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

FRICTION SHOCK-ABSORBING MECHANISM.

Application filed April 30, 1925, Serial No. 26,899. Renewed April 18, 1927.

This invention relates to improvements in friction shock absorbing mechanisms.

One object of the invention is to provide a friction shock absorbing mechanism especially adapted for railway draft riggings having graduated action during the compression stroke, including heavy final frictional resistance produced by relative movement of a plurality of friction elements, wherein the 10 friction elements are movable as a unit during one of the stages of compression to effect relatively light resistance, the relative movement of the plates being subsequently produced by arresting movement of certain 15 of said plates, while permitting continued movement of the remaining plates relatively thereto.

A further object of the invention is to provide a mechanism of the character indicated, 20 including a plurality of relatively movable friction plates and means in the form of a stop column having limited movement, to which certain of said parts are anchored to arrest movement of the latter plates while 25 permitting continued movement of the remaining co-operating plates.

Other objects and advantages of the invention will more fully and clearly appear from the description and claims hereinafter following.

In the drawings forming a part of this specification, Figure 1 is a longitudinal, sectional view of a portion of a railway draft rigging, showing my improvements in connection therewith, the section through the friction shell and wedge system being taken on two planes 120° apart. Figures 2 and 3 are vertical, transverse, sectional views corresponding respectively to the lines 2—2 and 40 3—3 of Figure 1. And Figure 4 is a rear end elevational view of the wedge member used in connection with my improved mechanism.

In said drawings, 10—10 indicate channel-shaped center or draft sills of a railway car underframe to the inner faces of which are secured front stop lugs 11—11 and rear stop lugs 12—12. The inner end portion of the drawbar is designated by 13, to which is op-

eratively connected a hooded yoke 14 of well-known form. The shock absorbing mechanism proper, hereinafter more fully described, and front and rear followers 15 and 16 are disposed within the yoke. The yoke and the parts therewithin are operatively supported by a detachable saddle plate 17 supported from the draft sills. The friction shell employed in connection with my improved mechanism is preferably of cylindrical form and in order to properly center and guide the same between the draft sills, a pair of guide plates 18 are disposed on opposite sides thereof, the same being suitably secured to the corresponding center sills.

My improved shock absorbing mechanism 65 comprises broadly a combined friction shell and spring cage A; a wedge B; three friction shoes C—C—C; two sets of friction plates D and E; a stop column element F; a main spring resistance G; a relatively lighter additional spring resistance H; a spring follower ring K; and a retainer bolt L.

The combined friction shell and spring cage is in the form of a substantially cylindrical casting having a transverse rear end 75 wall 118 co-operating with the rear follower 16. The friction shell section 19 is formed at the forward end of the casting A, the spring cage proper being formed rearwardly thereof. The friction shell 19 has three interior cylindrical friction surfaces 20 converging inwardly of the mechanism.

The wedge B is in the form of a relatively heavy cast block suitably cored as indicated at 21. The block B is provided with a transverse flat outer face 22 adapted to bear on the inner side of the main follower 15. At the inner end, the wedge block B has three rearwardly converging wedge faces 23—23 80 symmetrically disposed about the axis of the mechanism. An annular flange 24 is provided at the outer end of the wedge, the flange being adapted to engage and bear on the outer ends of the friction plates D.

The three friction shoes C are of like design, each shoe having a longitudinally disposed outer true cylindrical friction surface 95 25 adapted to co-operate with the corre-

sponding friction plate E. On the inner side, each shoe has a wedge face 123 correspondingly inclined to and adapted to co-operate with one of the wedge faces 23 of the block B. At the rear end, each shoe C has a flat transverse face 26 forming an abutment for the outer end of the spring resistance coil H.

The friction plates D and E are disposed 10 between the wedge friction shoes and the friction surfaces of the shell 19. The plates D which are three in number, are all of like design, each plate being curved in transverse section and having true cylindrical outer and inner friction surfaces, the outer friction surfaces thereof co-operating with the corresponding friction surfaces 20 of the friction shell and the inner friction surfaces co-operating with the plates E which are interposed between the same and the wedge friction shoes. The plates E which are also 15 three in number, are arranged in annular series and each plate is also of curved cross-section, having outer and inner true cylindrical friction surfaces co-operating respectively with the inner friction surface of the corresponding plate D and the cylindrical friction surface of the corresponding wedge block C. At the inner end, each plate E has 20 an inwardly projecting flange 27, the flanges of the three shoes forming a substantially complete annulus. In this connection, it is pointed out that the friction plates D are of greater length than the friction plates E and 25 in the normal position of the parts have their front and rear ends projecting beyond the latter.

The stop column F is in the form of a cylinder open at its front end and having 30 an annular shoulder 28 at the rear end thereof. The rear end wall of the stop column has an opening 29 therein adapted to freely accommodate a boss 30 inwardly projecting from the rear wall 118 of the casting A. At the front end, the stop column is provided with a pair of spaced annular flanges or ribs 31 and 32, the rib 32 being considerably heavier than the rib 31 and spaced inwardly therefrom, leaving an annular groove 35 33 between the ribs to receive the corresponding flanges 27 of the plates E, the plates E being thus anchored to the stop column element for movement in unison therewith. It will be evident that the heavy annular rib 32 serves as a substantial abutment for the inner ends of the friction plates E while the mechanism is being compressed. Outward movement of the stop column element F is limited by a disk 34 abutting the boss 30 and engaging the annular shoulder 28 of said column, the disk 34 in turn being held seated by the spring resistance H.

The spring follower K is in the form of a relatively heavy ring having the opening 40 thereof of sufficient diameter to freely ac-

commodate the cylindrical portion of the stop column element F. The ring K is interposed between the main spring resistance G and the inner ends of the outer series of friction plates D.

The main spring resistance G which is in the form of a relatively heavy coil, has its opposite ends bearing respectively on the end wall 118 of the spring cage section of the casting A and the inner side of the follower ring K. The spring G is normally under initial compression, being so held by the follower ring K which bears on the inner ends of the plates D which in turn bear on the annular flange 24 of the wedge block B.

The spring resistance element H is disposed within the column element F and has its front end bearing on the inner ends of the friction wedge shoes. This spring is lighter than the outer spring G and has its front end extending beyond the corresponding end of the column as most clearly shown in Figure 1.

The mechanism is held under initial compression and maintained of uniform overall length by the retainer bolt L which has the rear end thereof anchored within the hollow boss 30 on the end wall 118 of the spring cage and its front end anchored to the wedge block B, the nut of the bolt being slidably accommodated within the opening 21 of said block. The head end of the bolt, which is disposed within the hollow boss is also movably accommodated therein.

The normal position of the parts in full release is that shown in Figure 1, wherein the outer series of plates D is shown as abutting the annular flange on the wedge B, the spring follower ring abutting the inner ends of said plates, and the annular shoulder 28 of the column element abutting the disk 34, thereby positioning the innermost series of friction plates E in their outer position. It is also pointed out that when the parts are in normal position, there is a slight clearance between the annular rib or flange 32 and the spring follower ring K.

The operation of my improved shock absorbing mechanism, assuming a compression stroke, is as follows: The followers 15 and 16 will be moved relatively toward each other, thereby carrying the wedge B, wedge friction shoes C and friction plates D inwardly of the friction shell in unison, at the same time setting up a wedging or lateral spreading action between the wedge and friction shoes, placing the friction plates D and E under lateral pressure. As the wedge block B, friction plates D and wedge friction shoes C are carried inwardly of the mechanism, due to the friction created between the plates D and E and shoes C, the plates E will also be carried inwardly in unison therewith, thus carrying the column 120

F rearwardly. During this action, both the main spring G and the spring H will be compressed, and there will also be a slight slippage of the friction shoes on the wedge faces of the wedge B, due to the same being moved laterally inwardly toward the axis of the mechanism, on account of the converging relation of the friction surfaces 20 of the friction shell. The shoes will thus be advanced 5 slightly relatively to the wedge member B. The described action will continue until the inner end of the stop column comes into engagement with the inner face of the end wall 118 of the spring cage, whereupon movement 15 of the friction plates E will be positively arrested. Continued inward movement of the wedge B will cause the friction shoes and the friction plates D to be moved inwardly relatively to the friction shell and 20 the now stationary plates E, thereby greatly augmenting the frictional resistance. The compression of the mechanism will continue as described either until the actuating force is reduced, or the main front follower 15 comes into abutment with the front end of 25 the casting A, whereupon the actuating force will be transmitted directly through the casting to the rear follower 16, the casting A functioning as a stop column to prevent 30 the springs G and H from being driven solid.

Release of the mechanism will be assured by the spring H which bears directly on the wedge block C, thereby permitting release 35 of the wedging system independently of any movement of the friction plates. Expansion of the spring G will carry the plates D outwardly of the mechanism, the friction plates E being carried therewith due to the friction existing between the plates, outward 40 movement of the plates E being finally limited by engagement of the shoulder 28 of the stop column with the disk 34. Outward movement of the plates D will be arrested by the wedge B, the outward movement 45 of which in turn is limited by the retainer bolt L.

While I have herein shown and described what I now consider the preferred manner of carrying out my invention, the same is 50 merely illustrative and I contemplate all changes and modifications that come within the scope of the claims appended hereto.

I claim:

1. In a friction shock absorbing mechanism, the combination with a column-load-sustaining member; of a plurality of friction elements disposed at one end of said member, all of said elements being movable as a unit during the compression stroke; means having limited movement with reference to said member co-operating with the other end thereof for arresting movement of certain of said elements after a predetermined compression of the mechanism and permitting the remaining friction elements

to be moved relatively thereto; a follower, said follower and member being movable relatively toward and from each other; combined restoring and cushioning spring means; and lateral pressure creating means 70 co-operating with said friction elements for pressing the same into intimate frictional contact upon relative approach of said follower and member.

2. In a friction shock absorbing mechanism, the combination with a column load sustaining member; of a follower, said member and follower being movable relatively toward and from each other; a plurality of relatively movable friction elements 75 movable as a unit during relative movement of said member and follower during a predetermined compression of the mechanism; a second column to which certain of said elements are anchored, said second column having limited movement with reference to said column load sustaining member for arresting movement of said last named elements after said predetermined compression to 80 compel the remaining elements to move relatively thereto; a main spring resistance; and lateral pressure-creating means co-operating with said elements to place them under lateral pressure upon relative movement of said follower and column-load sustaining member, said lateral pressure creating means also having engagement with said remaining elements to effect movement thereof with reference to the column load sustaining member. 85

3. In a friction shock absorbing mechanism, the combination with a column load sustaining member; of a pressure transmitting element having wedge means associated therewith, said element and member being movable relatively toward and from each other; friction shoes co-operating with said wedge means; a plurality of relatively movable friction plates movable as a unit during relative movement of said member and element during a predetermined compression 100 of the mechanism; a second column member to which certain of said plates are anchored, said column member having limited movement with reference to said column load sustaining member for arresting movement of said last named plates after said predetermined compression to compel relative movement of said friction shoes and last named plates; abutment means on said pressure transmitting element adapted to engage the remaining plates to effect movement thereof inwardly of the mechanism during the entire compression stroke; and means yielding 105 opposingly opposing movement of said plates and friction shoes. 110

4. In a friction shock absorbing mechanism, the combination with a column-load-sustaining member; of a plurality of relatively movable friction plates; a lateral wedge pressure creating system co-operating 120

with said plates, said wedge pressure creating system and all of said plates being simultaneously movable inwardly of the mechanism during initial compression of the mechanism; means for arresting movement of certain of said plates after a predetermined initial compression, whereby the remaining plates and friction wedge system are moved relatively thereto during the remainder of the compression stroke; a spring resistance means operatively associated with said lateral pressure-creating system and plates.

5. In a friction shock absorbing mechanism, the combination with a friction shell having inwardly converging friction surfaces; of a pressure transmitting wedge means having abutment means associated therewith, said pressure-transmitting means and shell being relatively movable toward and from each other; sets of friction plates within the shell, one of said sets being engaged by said abutment means and movable in unison with said pressure transmitting means and the remaining plates having limited movement inwardly of the shell simultaneously with the outer plates; lateral wedge pressure creating means co-operating with said sets of plates, said pressure creating means including a wedge element and friction shoes engaging the innermost of said plates of said sets; means for arresting movement of said remaining plates after a predetermined compression of the mechanism; and spring resistance means operatively associated with said lateral pressure creating means and plates.

6. In a friction shock absorbing mechanism, the combination with a friction shell having inwardly converging friction surfaces; of a pressure transmitting wedge means having abutment means associated therewith, said pressure transmitting means and shell being relatively movable toward and from each other; sets of friction plates within the shell, one of said sets being engaged by said abutment means and movable in unison with said pressure-transmitting means and the remaining set having limited movement inwardly of the shell simultaneously with the other plates; lateral wedge pressure-creating means cooperating with said sets of plates; means for arresting movement of said remaining set of plates after a predetermined compression of the mechanism; and spring means operatively associated with said lateral pressure-creating means and plates.

7. In a friction shock absorbing mechanism, the combination with a friction shell having inwardly converging friction surfaces; of two sets of curved friction plates, the plates of one set frictionally co-operating with the plates of the other set, one of said sets of plates having limited movement

with reference to the shell; column means to which said last named plates are anchored, said column having limited movement with reference to said shell for arresting movement of the plates anchored thereto after a predetermined compression of the mechanism; lateral pressure creating means operatively associated with said plates; and spring resistance means operatively associated with said pressure means and plates.

8. In a friction shock absorbing mechanism, the combination with a friction shell having interior friction surfaces; of an annular series of friction plates co-operating with the friction surfaces of the shell, said plates and shell being relatively movable; a second annular series of friction plates co-operating with said first named plates, said last named plates and shell having limited relative movement; a column element to which said last named plates are anchored, said column and shell having limited relative movement for arresting movement of the plates anchored thereto after a predetermined compression of the mechanism; a lateral wedge pressure creating friction system co-operating with said last named series of plates; a main spring resistance co-operating with said two series of plates; and a second spring resistance co-operating with said wedge pressure creating system, said last named spring being disposed within said column element.

9. In a friction shock absorbing mechanism, the combination with front and rear stops; of a combined friction shell and spring cage having follower means associated therewith co-operating with certain of said stops; additional follower means co-operating with the remaining stops; a yoke enclosing said combined spring cage and friction shell and follower means; annular sets of friction plates within said shell, certain of said plates having limited longitudinal movement with reference to the shell; and the remaining plates being movable with reference to the shell during the entire compression stroke; wedge-pressure-creating means for placing said annular sets of plates under lateral pressure; and spring resistance means operatively associated with said wedge-pressure-creating means and plates.

10. In a friction shock absorbing mechanism, the combination with a friction shell having interior curved friction surfaces; of a pressure transmitting member, said member and shell being relatively movable toward and away from each other; a carrier having limited movement with reference to said shell; two sets of curved friction plates within the shell, said sets being relatively movable with reference to each other, certain of said plates being anchored to said carrier; means for limiting the relative movement of

said carrier and friction shell; lateral wedge pressure creating means co-operating with said said pressure transmitting means for placing the plates under lateral pressure, said lateral pressure creating means including a plurality of friction elements engaging the friction surfaces of the adjacent plates; and a spring resistance means co-operating with said lateral wedge pressure creating means.

In witness that I claim the foregoing I ¹⁰ have hereunto subscribed my name this 28th day of April, 1925.

JOHN F. O'CONNOR.
